OSCILLATING SYSTEM FOR IMPREGNATING SHEET MATERIAL

Edward W. Smith, Melrose Highlands, Mass.

Application March 11, 1952, Serial No. 275,954

12 Claims. (Cl. 68—175)

The present invention relates to equipment for the impregnation of porous materials, such as textile fabrics, with liquids.

In many textile processing procedures, such as washing, dyeing, bleaching, and the like, it is necessary to thoroughly impregnate the material being treated to ensure rapid and effective transfer of the liquid medium in and out of the fabric. Many methods and equipment have been designed and operated for this purpose, such as squeeze rolls under the level of the liquid or the to and fro motion of the goods in the liquid in a direction perpendicular to the plane of the goods.

This latter method in particular has been found to produce good results in certain instances but has been greatly reduced in its effectiveness because of the forces required to produce this type of motion in the goods at a rapid rate.

For efficient operation it is desirable to impregnate the material in a continuous operation process. One method is to move the material very slowly over a large vibrating surface to be assured that each part of the textile material is thoroughly treated. The material is usually moved slowly in such cases since the time the material is treated is inversely proportional to the speed of motion of the material. In the present invention the whole of the material in the impregnating bath is vibrated and therefore subjected directly to the impregnating forces developed in the liquid and applied to substantially all the material in the bath. This permits the material to be sent through the bath at a more efficient speed so that a greater amount of material can be treated than could otherwise under the slower method of the prior art.

The mechanical system of the present invention preferably incorporates features of the torsional drive disclosed in my U. S. Letters Patent No. 2,604,669, issued July 29, 1952, entitled Doffer Combs, which makes possible a simple and very efficient driving system.

A further advantage in the present invention is that by means of the mechanical moving system a balanced torsional effect is obtained between the mass at one end of a torsional rod and the mass at the other end so that the masses are most efficiently employed and all the energy in the system is useful energy.

A further advantage of the present system is that by adjusting the masses at each end of the torsionally oscillating system, a desired amplitude ratio may be obtained so that a chosen amplitude of motion may be reached.

The invention will be further described in the specification set forth below when taken in connection with the drawings forming a part thereof, in which:

Figure 1 shows somewhat diagrammatically an embodiment of the present invention corresponding to a section on the line 1—1 of Figure 2.

Figure 2 shows a transverse section of Figure 1.

Figure 3 shows a side view of the device of Figure 2 as seen from the left of Figure 2.

Figure 4 shows a plan view of a modified form of the invention shown in Figures 1-3 inclusive, and,

2

Figure 5 shows a section taken substantially on the line 5—5 of Figure 4, and,

Figure 6 shows a partial elevation looking upwards from the lower side of Figure 4.

5 The means whereby a substantial improvement in this respect has been effected in the present instance can best be understood from a reference to Figure 1, where 1 is a tank of suitable construction to hold the liquid involved. The incoming goods at A are passed over a series of rolls 2 and down into the body of the liquid where they pass around another series of rolls 3, thus making successive loops of the goods in the tank 1. In the present invention the goods in passing down into the liquid from rolls 2 to rolls 3, pass between pairs of narrow bars 4 which may conveniently be circular in cross section and which are supported and held at their ends by the T-shaped frames 5. Similarly, in passing upward again from rolls 3 to rolls 2, the goods may pass again between another pair of similar guide bars 4 which are also similarly supported and held at their ends by the T-shaped frames 5.

By reference to Figure 2 it will be noted that the T-shaped frames 5 are secured to a cylindrical torque tube 6. Passing through the torque tube 6, and concentric with it, is a torsion shaft 7 whose purpose will presently become clear. The torsion shaft 7 has secured to it by welding, or other suitable means, a flange 8 which is solidly secured to flange 9 on the end of the torque tube 6 by bolts 10.

On the inside of the other end of the torque tube 6, and concentric with it, is a sleeve or other suitable bearing 11 through which the torsion shaft 7 passes and in which it is free to angularly move with respect to the torque tube 6. On the opposite side of the torque tube 6 is disposed a bar 12 solidly secured at its ends to extensions of the T-shaped members 5, and acts as a counterbalance for the guide bars 4 and 4 so that the axis of rotation of the system passes through the center of gravity.

At the outer end of torsion shaft 7, and beyond the point where it passes through the bearing 11, an inertia element 13 is solidly secured to the torsion shaft 7, as for instance by means of the radial bolts 22, Figure 3. The moment of inertia of element 13 with weights 15 at each end may be conveniently chosen to be the same as the inertia of the combination consisting of guide bars 4 and 4, T-shaped frames 5, which together with the guide bars from the yoke, torque tube 6, and counterbalance 12, which while surrounding and concentric with torsion shaft 7, is solidly secured to the opposite end of the torsion shaft 7 as has already been explained. The whole arrangement is supported on bearings 14 in which it is free to turn.

If, now, a sinusoidally oscillating torque as explained below is applied to the end of the torsion shaft 7 at the point where it is secured to inertia element 13, inertia element 13 will oscillate torsionally about the axis of shaft 7 and in so doing will twist shaft 7.

The above described arrangement consisting of the inertia element 13 secured at one end of the torsion shaft 7, the other end of which is solidly secured to the assembly consisting of guide bars 4 and 4, T-shaped frames 5, torque tube 6, and counterbalance 12, constitutes a torsionally resonant system having two degrees of freedom, i. e. during oscillation the inertia element 13 oscillated at the same frequency as the assembly just described, but in the opposite direction when the oscillating torque mentioned above as being applied to the end of torsion shaft 7 has the same frequency as the natural period of the system. Thus when the inertia element 13 is moving counterclockwise, the assembly just described is moving clockwise and vice versa. Furthermore the angular amplitude of the two ends of torque

shaft 7 will be inversely proportional to the inertias to which they are connected.

The method by which the sinusoidally oscillating torque may be applied to inertia element 13, and consequently to that end of shaft 7, and the method whereby a multiplicity of such systems may be made to operate from a single driving source, is shown in Figure 3.

A connecting rod 16 is secured to one of the inertia weights 15, at the end of inertia element 13 via a bearing 17, and a similar bearing 18 is provided at the other end of crankshaft connecting rod 16 which secures it to eccentric 19 rotating on shaft 20. If a multiplicity of such torsionally oscillating systems are to be driven from the same source, this can conveniently be done by connecting the second, or more, systems to the first by the use of interconnecting rods 21. By this means as many of the torsionally oscillating systems as may be desired, may be driven from the same source.

Coming now to the design of a specific system, it will be assumed that a desired frequency of oscillation has been chosen and also the maximum amplitude of oscillation either side of the neutral position. The maximum torque required to give the necessary acceleration to the inertia of the combination consisting of the guide bars 4 and 4, frames 5, torque tube 6, and counterbalance 12 may be determined from the relationship

$$\text{Torque} = 12J_m\omega^2$$

where "torque" is the maximum torque in inch pounds required to give the necessary maximum acceleration, J_m is the mass moment of inertia in pound feet squared of the above described combination, ω is 2 times the desired frequency of oscillation in cycles per second, and is the angular amplitude of motion in radians.

Having thus determined the maximum torque needed, the next step may conveniently be to determine the diameter of the torsion shaft. In this connection it is well to remember that such a machine may well be called upon to operate on a 24 hour per day basis, for which reason the maximum fiber stress in the shaft should be kept at a relatively low figure which I prefer to set at 10,000-15,000 pounds per square inch. Assuming that the lower figure is chosen the shaft diameter may be determined from the following relationship

$$d = \frac{16T}{10,000}$$

where d is the torsion shaft diameter in inches, T the maximum torque in inch pounds already determined, and the factor 10,000 is, of course, the fiber stress value chosen.

The required length of the torsion shaft may then be determined from the relationship

$$L = \frac{(3400d^2)^3}{Jf^2}$$

where L is the length of the torsion shaft from the nodal point to the point where it is solidly secured to the inertia system being driven, i. e. to the flange 8, d is the shaft diameter in inches just obtained, J is the moment of inertia on a weight basis of the combination of guide bars 4 and 4, frames 5, torque tube 6 and counterbalance 12, f is the frequency of oscillation in cycles per second, and the factor 3400 derives from the assumption that the shaft is made of a material having a torsional modulus of elasticity of 12,000,000 lbs. sq./in.

Earlier it was pointed out that the inertia of inertia element 13 may conveniently be chosen to be the same as that of the driven combination in which case the nodal point will occur at the midpoint of torsion shaft 7, i. e. half-way between the flange 8 and the point where the inertia element 13 is secured to shaft 7. In other words, the total length of the shaft 7 under these conditions between the above points will be twice the value of L as determined above.

While, as has been mentioned above, I prefer to make the inertia of element 13 the same as the driven system thus bringing the nodal point to the center of the active portion of shaft 7, it is possible to permit of a certain amount of variation in this respect. Thus if it is found that the value of L , or rather of $2L$, becomes conveniently long under a given set of conditions, this situation may be alleviated by making the inertia of inertia element 13 greater than that of the driven system. Under these conditions the distance between the nodal point and the point where inertia element 13 is secured to the torque shaft 7 may be reduced because the ratio of this distance to the distance between the nodal point and the flange 8 is inversely proportional to the ratio of the inertia of element 13 to the inertia of the driven system.

It will be understood from the above that in the above described arrangement, the initial effect of the eccentric at starting is to supply energy to the oscillating system consisting of a shaft 7 on one end of which is secured the inertia element 13 and on the other end of which is secured the system to be oscillated. Since, as has been already mentioned, at resonance the two inertias just described are moving at all times in opposite directions, they therefore are twisting the torsion shaft 7 in opposite directions at either end so that as a result the nodal point stands still. In effect, therefore, the eccentric supplies initially sufficient energy to supply the necessary kinetic energy to the moving inertias which energy is transferred back and forth from kinetic energy in the moving inertias to potential energy in the twisted shaft at the end of the stroke where momentarily the inertias are at rest.

Thereafter the eccentric supplies only energy used up in friction losses in moving the goods through the liquid which is many times less than what would be required to move the frame in addition at each stroke as is the case with the ordinary method.

A modification of the arrangement shown in Figures 1, 2 and 3 is shown in Figures 4, 5 and 6. In this case the oscillations of the rolls through which the material is passed in the tank is moved up and down and a somewhat simplified drive is used.

A drive shaft 30 is mounted similarly to the drive shaft 7 of Figure 2 with a bearing support 31 at one end of the tank, the non-driving end and another bearing 32 at the opposite side of the tank through which the shaft extends for connection with the oscillating drive. This is shown more clearly in Figure 6 and comprises a hub 33 in which the shaft 30 is firmly secured, which hub carries two inertia balancing masses, 34, 34, at the ends of arms 35, 35, extending from the sides of the hub along the tank.

A further arm 36 extends downward from the hub 33 and has at its end a disk plate 37 which has a pivoting pin 38 to which the link shaft 39 is attached which is driven by an eccentric drive similar to that shown in Figure 3. The drive shaft 30 has a plate 40 similar to the plate 8 welded to it, and plate 40 has a series of rivets 41 secured to a flange 42 of a torque tube 43 similarly as shown in Figure 2. The torsion shaft 30 which develops its maximum torsional amplitude at the plate 40, imparts this movement to the torque tube 43 which at its other end adjacent the bearing 32 is free to oscillate on the self lubricating bearing 44. Extending from the tube 43 adjacent the sleeve 44 are two substantially horizontal arms 45 and 46 which are rigidly attached to the torque tube 43. These arms 45 and 46 carry horizontal slots 47 and 48 respectively (Figure 5), in which pins 49 and 50 carried by the vertical bars or rods 51 and 52 respectively, engage. These upwardly extending rods 51 and 52 move in guide bearings 53 and 54. The rods 51 and 52 carry at their bottom, brackets 55 and 56 in which are mounted a plurality of pairs of rolls. Each bracket 55 and 56 shows three pairs of rolls, 57, 58, 59 on the bracket 55, and 60, 61 and 62 on the bracket 56.

The structure just described is at both sides of the

tank and the rolls, 57, 58 and 59 and 60, 61 and 62, extend across the tank at substantially the same level set in similar supporting members. These pairs of rolls permit the sheet material 63 to pass between them. The rolls may be spring tensioned against one another as by springs shown diagrammatically at 89, 80, or mounted so as to provide a desired grip or pressure on the material. The material 63 may be fed between a pair of feed rolls 63', 64, down into the tank around a roll 65 and then directly through both frames through a roll 66 and out through the end rolls of the system 67, 67.

In the operation of the device in accordance with Figures 4, 5 and 6, the arms 45 and 46 on both ends of the tank will be oscillated by the torque tube 43 to provide movement concentric with the shaft 30. As the shaft is driven by the eccentric drive the arms 51 and 52 will reciprocate up and down and oscillate the brackets 55 and 56, forcing the liquid in the tank into and through the sheet passing through the sets of gripping rolls which are supported in the brackets 55 and 56.

In the design in Figures 4, 5 and 6, each half of the oscillating mechanism is balanced by the other half and therefore there is no need for larger inertia balancing elements for the oscillatory system.

Having now described my invention, I claim:

1. In a system for impregnating sheet material with liquid, an oscillatable system comprising a yoke formed of a pair of parallel guide bars between which a sheet may be drawn, a torsionally oscillatable rod, bearing means for supporting said oscillatable rod parallel with said bars, a tube coaxial with said rod having arms attached thereto for supporting said guide bars, means rigidly attaching said rod and tube together at one end of the rod, means supporting the tube on said rod at the other end of the rod with a bearing positioned between the rod and the tube to permit oscillation of the tube, means for oscillating said rod at its unattached end for providing oscillation of said guide bars and said sheet material.

2. In a system for impregnating sheet material with liquid, an oscillatable system comprising a yoke formed with an arm and a pair of parallel guide bars between which a sheet may be drawn, torsionally elastic oscillatable rod, bearing means for supporting said oscillatable rod parallel with said bars, means for oscillating the oscillatable rod at one end, means connecting the oscillating rod at the other end to said arm, said oscillating rod serving as an elastic member, and the yoke attached at the other end serving as inertia mass for an oscillating resonant system embraced by said mass and elastic member.

3. In a system for impregnating sheet material with liquid, an oscillatable system comprising a yoke formed with a pair of parallel guide bars between which a sheet may be drawn, a torsionally elastic oscillatable rod, bearing means mounting said rod parallel with said bars, means for oscillating the oscillatable rod at one end, comprising an inertia counterbalancing bar mounted perpendicular to said oscillatable rod and secured to the same, a link member pivotally connected to said bar, a connecting rod linked to said link member and an eccentric drive connected to said connecting rod for imparting oscillatory movement to said oscillatable rod, means connecting the oscillatable rod at the other end to said yoke, said oscillatable rod serving as an elastic member, and the yoke attached at the other end serving as inertia mass for an oscillatory resonant system embraced by said mass and elastic member.

4. In a system for impregnating sheet material with liquids, an oscillatory system comprising a plurality of yoke members each having a pair of parallel guide bars between which a sheet material may be successively passed, a torsionally oscillatable shaft for oscillating each pair of yoke members, means connecting each torsionally oscillatable shaft to each pair of said yoke members, a connecting bar connected to each of said oscillatable 75

shafts, a movable link system connecting together said connecting bars, an eccentric, a connecting rod connected between the eccentric and said link system and means for driving said eccentric.

5. In a system for impregnating sheet material with liquids, an oscillatory system comprising a plurality of yoke members each formed of a pair of parallel guide bars between which a sheet material may be successively passed, a torsionally oscillatable shaft for oscillating each pair of yoke members, a frame structure for supporting each pair of yoke members including a tube coaxial with said oscillatable shaft and attached at one end thereto, and arm members rigidly securing said yoke members to said coaxial tube, a connecting bar connected to each oscillatable shaft at their ends and means for driving in tandem said connecting bars with reciprocating motion.

6. In a system for impregnating sheet material with liquids, an oscillatory system comprising a plurality of yoke members each formed of a pair of parallel guide bars between which a sheet material may be successively passed, a torsionally elastic oscillatable shaft for oscillating each pair of yoke members, a frame structure for supporting each pair of yoke members including a tube coaxial with said oscillatable shaft and attached at one end thereto, and arm members rigidly securing said yoke members to said coaxial tube, a connecting bar connected to each of said oscillatable shafts at their other ends and means for driving in tandem said connecting bars with reciprocating motion, each oscillating shaft serving as an elastic member and the yoke attached at the other end serving as inertia mass providing an oscillatory resonant system embraced by said mass and elastic members, said masses having selected magnitudes providing amplitudes of oscillation in substantial reverse ratio thereto.

7. In a system for impregnating sheet material with liquids, an oscillatable system comprising a yoke formed of a pair of parallel guide bars between which a sheet may be drawn, a torsionally elastic oscillatable rod, bearing means for supporting said oscillatable rod, means connecting the oscillatable rod at one end to said guide bars, said oscillatable rod serving as an elastic member, means for oscillating the oscillatable rod at one end thereof with the yoke attached at the other end, said last mentioned means and yoke having effectively equal mass magnitudes whereby the resonant system embraced by said masses and elastic members provides a balanced resonant system.

8. A system for impregnating porous sheet material with liquid comprising a tank adapted to contain the liquids used in the impregnating system, a plurality of parallelly spaced rolls arranged alternately in the upper and lower sections of the tank and positioned to permit a sheet to be drawn over and under the same, a plurality of guide bars arranged in pairs between which pairs said sheet may be passed, a supporting bar at each end of said tank for supporting the ends of each pair of guide bars, a plurality of torsionally oscillatable rods, bearing means mounting said rods on said tank with said rod substantially parallel to said guide bars, a sleeve coaxial with each oscillatable rod having one end secured thereto and the other end freely mounted on said rod, said supporting bars each being rigidly secured to one of said sleeves, and means for torsionally oscillating said rods applied at the end not connected with said sleeve.

9. A system for impregnating porous sheet material with liquid comprising a tank adapted to contain the liquid used in the impregnating system, a plurality of parallelly spaced rolls arranged alternately in the upper and lower section of the tank and positioned to permit a sheet to be drawn over and under the same, a plurality of guide bars arranged in pairs between which pairs said sheet may be passed, a supporting bar at each end of said tank for supporting the ends of each pair of guide bars, a plurality of torsionally elastic oscillatable rods, bearing means mounting said rod on said tank with said rods substan-

tially parallel to said guide bars, a sleeve coaxial with each oscillatable rod having one end secured thereto and the other freely mounted on said rod, said supporting bars being rigidly secured to said sleeves and means for torsionally oscillating said rods applied at the end not connected with said sleeve, forming a torsionally resonant system in which each oscillating rod provides an elastic member and the yoke attached at the end of the rod provides inertia mass forming a balanced resonant system.

10. In a system for impregnating sheet material with liquid, an oscillatory resonant system comprising a yoke formed with pairs of parallel guide bars between which a sheet may be drawn, means for imparting reciprocating movement to said sheet substantially normal to its surface including an elastic rod, means attached at one end of said elastic rod for imparting said reciprocal movement to said elastic rod, and means attached at the other end of said elastic rod for reciprocally oscillating said yoke, said last two means having effective mass magnitudes for establishing balanced resonance in said system.

11. In an apparatus for impregnating sheet material with liquid, an oscillatory resonant system for imparting reciprocating movement to a sheet which may be positioned substantially normal to its surface, comprising means adapted to engage the surface of the sheet for imparting oscillating vibrations thereto, means supporting said engaging means, a torsionally elastic member attached at one end to said supporting means, and means for providing a mass magnitude attached at the other end of said elastic member having substantially the same 30 inertia as said previously mentioned supporting means and the means engaging the surface of the sheet, completing

8
said oscillatory resonant system, and means for supplying oscillating vibrations to said system at substantially the resonant frequency of said system.

12. In an apparatus for impregnating sheet material with liquid, an oscillatory resonant system for imparting reciprocating movement to a sheet which may be positioned substantially normal to its surface, comprising means adapted to engage the surface of the sheet for imparting oscillating vibrations thereto, means supporting said engaging means, a torsionally elastic member attached at one end to said supporting means, and means for providing a mass magnitude attached at the other end of said elastic member for establishing a resonant system, and means for supplying oscillating vibrations to said system at substantially the resonant frequency of said system.
